CLAIM

The ornamental design for a vehicle windshield washer nozzle, as shown and described.

DESCRIPTION

FIG. 1 is a side elevational view of the vehicle windshield washer nozzle of the present invention, the dashed elements being not normally visible when in use and forming no part of the present design,

FIG. 2 is front elevational view of the vehicle windshield washer nozzle of the present invention,

FIG. 3 is a rear view in elevation of the vehicle windshield washer nozzle of the present invention,

FIG. 4 is a reduced perspective view of the vehicle windshield washer nozzle, shown mounted on the hood of a car. The broken line showing of the car is for illustrative purposes only and forms no part of the claimed design; and, FIG. 5 is an isometric perspective view of a vehicle windshield washer nozzle incorporating the invention.
